UNITED STATES PATENT OFFICE.

PHILIP M. ARMSTRONG, OF PATERSON, NEW JERSEY, ASSIGNOR TO THE HAYWARD COMPANY, OF NEW YORK, N. Y., A CORPORATION OF NEW YORK.

BUCKET.

1,218,826.

Specification of Letters Patent. Patented Mar. 13, 1917.

Application filed May 9, 1914. Serial No. 837,383.

To all whom it may concern:

Be it known that I, PHILIP M. ARMSTRONG, a citizen of the United States, residing at Paterson, in the county of Passaic

5 and State of New Jersey, have invented certain new and useful Improvements in Buckets, of which the following is a full, clear, and exact specification, such as will enable others skilled in the art to which it

10 appertains to make and use the same.

This invention relates to excavating buckets, and while I have shown, and will more particularly describe it, as applied to a dwarf or hand operated orange peel 15 bucket, it is to be understood, that it may be applied to other types of buckets as well as the orange peel, and also to standard or full sized, power operated buckets.

The use of dwarf, or hand operated 20 orange peel buckets has now become quite general, being especially adapted for use where the operating space is limited, as for example, in foundation work, tunnel excavations and the like, where they are frequently used for excavating rock, earth or other materials, from small steel cylinders which are driven into the ground preparatory to forming piles, by depositing concrete therein. One serious drawback to the 25 use of dwarf orange peel buckets, in such work, has been that owing to the small size of the buckets, and their relatively small weight, compared to the standard or full sized buckets, their capacity for penetrat-

30 35 ing the ground when hard material is encountered, is greatly lessened, and one of the objects of my invention is to overcome this difficulty.

I accomplish the desired result by providing means at the head of the bucket for applying force thereto, to drive the digging points of the blade into the material to be excavated, when occasion requires.

A further object of my invention is to 40 45 apply this force by means of a device which may be readily detached from the head of the bucket so that the bucket may be used in the ordinary way without this attachment, when there is no necessity for its use.

50 Another object of my invention is to provide an attachment of the character stated, which is simple and economical to make, to apply, and to operate, and in no wise interferes with the usual operation of the bucket 55 to which it is applied.

All of these objects will be readily apparent from the following description, taken in connection with the accompanying drawings, in which—

Figure 1, is a side elevation of a dwarf 60 orange peel bucket with my driving attachment secured thereto;

Fig. 2, is a section on line 2—2 of Fig. 1, in the direction of the arrows;

Fig. 3, is a plan view on line 3—3 of 65 Fig. 1;

Fig. 4, is a horizontal detail section on line 4—4 of Fig. 1; and

Fig. 5, is an elevation of a shackle for use when the driving attachment is detached from the bucket.

Referring to the construction illustrated, A, represents in its entirety, an orange peel bucket, of a usual and well known type, of which only a brief description will be necessary. It comprises a supporting head, B, connecting rods C, pivotally suspended therefrom, a plurality of digging blades D, a power wheel E, rotatably mounted in a frame F, said power wheel being rotated by 75 a closing line G, and, with the frame F, raised and lowered by means of side chains H, which wrap about a hub I, on each side of the power wheel, the arrangement being such that as the power wheel E and the 80 frame F are raised and lowered, the digging blades D, are respectively closed and opened.

Referring now in detail to the novel features illustrated in the drawings, and more 90 clearly shown in Figs. 2, 3 and 4, these features comprise a hammer or weight member H', which I prefer to have spherical or ball-shaped, provided at its central portion with a bore I', a guide therefor, indicated at J, 95 which at its lower end, is exteriorly threaded at J', and secured to a weight guide socket K, by means of the interior threads J² therein, which guide socket is adapted to be removably secured to the head B of the 100 bucket. The weight guide socket K, comprises an impact block, of circular form, K' (see Fig. 4) from which are depending side lugs, K² K³, which are adapted to rest upon the head B of the bucket, and are secured 105 thereto by means of bolts K⁴ passing through the lugs K² K³ and through an upwardly projecting lug K⁵ on the bucket head. The guide J is formed with an external shoulder L, and the inner wall of the 110

weight H' is formed with a shoulder M , so that when the weight H' is raised, the shoulder M contacts with the shoulder L , and thereby is prevented from riding off the guide. A portion of the shoulder L , at each side thereof, indicated at L' , as well as the opposing walls L^2 of the weight H' are plane surfaces to prevent rotative movement thereof, on the guide J .

10 The guide J is formed with a longitudinal bore therethrough, indicated at N , through which may pass the closing rope G .

15 The weight H' is recessed at each side thereof to receive the ends of a shackle O , secured thereto by bolts P .

20 The weight may be manipulated by grasping the shackle O , or, when the operation is below the surface or if the bucket be power operated, by means of a rope Q , secured to the shackle, operated by hand or other power.

25 The shackle O is so formed that when in operation the pull thereon is at directly opposite sides of the weight H' , and when not in operation, it takes its place by gravity at one side so as to be out of line, and not interfering, with the closing rope, G .

30 Dwarf orange peel buckets for such purposes as stated herein, I have found to work very satisfactorily with a hammer device, weighing approximately one third the total weight of the bucket without the hammer device.

35 The operation of the device is as follows: Assuming that the bucket is on the material to be excavated, and in the open position shown in Fig. 1, and assuming that the material is too hard to permit ready penetration of said material by the blades, the shackle O is either manually grasped by the operator, or manipulated through the rope Q attached thereto, to lift the weight H' to the position indicated in dotted lines in Fig. 1, the same sliding on the guide J ; 40 it is then released, and, in falling, it imparts a blow to the face K' of the weight guide socket K , which blow is transmitted through the lugs K^2 K^3 to the supporting bucket head B , and thence, through the rods C to the blades D . A few blows thus given will suffice to drive the digging points of the blades D , into the material. The closing line G , is then actuated to rotate the power wheel E , the chains H winding upon the hub members I , raising the frame F , thereby closing the blades, and in this operation it will be seen that as the rope G , passes through the bore of the guide J , its operation is in no wise interfered with by the weight H . When the bucket is closed, the rope Q , may be operated as a holding line (in conjunction with the rope G) and in so doing, the weight H' will rise to the position indicated in dotted lines in Fig. 1, and will 45 be so held until the bucket has been swung

to a position where the material is to be dumped, when the closing line G is eased off to permit the opening of the blades, and, so held, the bucket is swung into position to take a new load of material.

70 When the bucket is to work in material easily penetrated, and it is unnecessary to use the hammer device, the bolts K^4 may be removed, the hammer device lifted from its position on the head of the bucket, the shackle R , (shown in Fig. 5) secured to the head K^5 by means of the centrally located bolt K^4 and the bucket operated in the ordinary way.

75 I desire it to be understood that I do not confine myself to the precise details of construction and arrangement of the invention herein set forth, as modifications and variations may be made without departing from the spirit of the invention, as defined by the appended claims.

80 What I claim is:

1. In an excavating device, the combination of a supporting head, a plurality of digging members, means connecting said head and said digging members, mechanism for closing the latter, an impact block having an opening therethrough, means for detachably securing said block to said head, a hollow guide rigidly secured to said block, a weight member adapted to slide on said guide, means for lifting and releasing said weight member to make driving contact with said block, and a line for operating said closing mechanism, passing centrally through said supporting head and through said block, guide and weight member.

90 100 105 110 115 120 125 130

2. In an excavating device, the combination of a supporting head, a plurality of digging members, supporting means connecting said head and said digging members, closing mechanism having operative connection with said head and said digging members, a line connected to said closing mechanism for operating the same, an impact block detachably connected to said head, a guide rigidly secured to said block and bored for the passage of said line therethrough, and a weight member bored to slide on said guide and for the passage of said line therethrough, portions of said guide and weight member having plane surfaces to prevent rotation of the latter.

3. In an excavating device, the combination of a supporting head, a plurality of digging members, supporting means connecting said head and said digging members, closing mechanism having operative connection with said head and said digging members, a line connected to said closing mechanism for operating the same, an impact block detachably connected to said head, a guide rigidly secured to said block and bored for the passage of said line therethrough, a weight member bored to slide on said guide and for the

passage of said line therethrough, and self-contained means on the lower part of said guide and the upper part of the weight member for limiting the upward movement 5 of said weight member on said guide.

4. In an excavating device, the combination of a supporting head, a plurality of digging members, means connecting said head and said digging members, mechanism 10 for closing the latter and having operative connection therewith and with said head, an impact block, means for detachably securing said block to said head, a hollow guide rigidly secured to said block, a weight member 15 adapted to slide on said guide, said guide normally lying completely within said weight member, means for lifting and releasing said weight member to make driving contact with said block, a line for operating said closing mechanism, passing through said supporting head and through said block, guide and weight member, and flanged and shouldered portions on said 20 guide and weight member to limit the lift-

ing movement of the weight member on said 25 guide.

5. In an excavating device, the combination of a supporting head, a plurality of digging members, means connecting said head and said digging members, mechanism 30 for closing the latter and having operative connection therewith and with said head, an impact block, means for detachably securing said block to said head, a hollow guide rigidly secured to said block, a weight 35 member bored to slide on said guide, a line for operating said closing mechanism, passing through said head and through said block, guide and weight member, and a bail member secured to said weight at diametrically opposite sides of its bore and adapted to take, by gravity, when not in operation, a position out of alignment with the bores 40 of said weight and guide.

PHILIP M. ARMSTRONG.
